UNITED STATES PATENT OFFICE.

FREDERICK WILLIAM PARSONS, OF CLEVELAND, OHIO, ASSIGNOR TO THE PARSONS-JACKSON COMPANY, OF CLEVELAND, OHIO, A CORPORATION OF OHIO.

DOLL.

1,136,482.

Specification of Letters Patent.

Patented Apr. 20, 1915.

Application filed May 12, 1913. Serial No. 767,144.

To all whom it may concern:

Be it known that I, FREDERICK WILLIAM PARSONS, citizen of the United States, residing at Cleveland, in the county of Cuyahoga and State of Ohio, have invented certain new and useful Improvements in Dolls, of which the following is a specification.

This invention has reference to dolls, and is an improvement on the doll shown and 10 claimed in my application, Ser. No. 679,818, filed February 26, 1912, all substantially as shown and described and particularly pointed out in the claims.

In the accompanying drawings, Figure 1 15 is a front partially sectioned elevation of the doll, and Fig. 2 is a vertical central sectional elevation thereof, front to rear. Fig. 3 is a detail of the body alone, and Fig. 4 is a detail of one of the legs, partially sectioned at its top. Fig. 5 is a perspective view of one of the two leg connections as hereinafter fully described.

The invention herein resides mainly in important details of construction which constitute the material difference and improvement over the invention disclosed in my said former application, and one of these details consists in the collar *c* at the top of the body *b* and which provides a seat for neck *n* on head *h*. The said collar is original and peculiar in this particularly that it has a special bead 2 inside about the said collar which provides a uniform reinforcement and strengthening medium to protect the collar 35 against splitting or cracking. Of course the body of the doll is a mere shell and no heavier than is actually required to give it the requisite stiffness and durability, and hence a distinct reinforcement or internal 40 enlargement is required in the collar as otherwise it is too weak for service and exceedingly liable to be split or broken especially when the doll is allowed to fall on its head or head down, as frequently occurs 45 with children. The construction or taper of the neck *n* where it seats on the collar contributes to this effect, but with the bead 2 inside as shown such cracking or splitting of the collar does not occur. The said bead 50 therefore is regarded as an essential and important improvement. Again, the connection of the arms *a* with the body and with each other is deemed original and important and materially different from what is shown in the original application or otherwise known. Thus, the said arms have a ball and socket joint with the body *b* and the balls 3 are on the body and the socket in the arms. This is material both in the construction and the operation of the doll for 55 the reason that the connections between the arms consisting of the spring 4 and straight links 5 are swiveled in the wall of the arms at the extremities of said connections, thus providing for the free rotation of each arm 60 indefinitely without in any manner affecting the other arm or the connections between them as well as adapting the arm to rock freely within limits on its bearing or ball. To these ends a suitable spring 4 is employed and which in this instance is of a straight spiral pattern rather closely wound and of strength sufficient to hold the arms in working position, and the links 5 are of 65 wire engaged at their ends with said spring 70 and provided with suitable beads at their outer ends swiveled in the arms behind suitable metallic washers 7 and disks 8 overlapping the edges of said washers and cemented or otherwise permanently adhered 75 to the said arms. The same or similar links 5 and washer and disk are employed in connection with the legs 1, but the connections between the links 5 differ from those of the arms as will presently be seen. 80 The balls 3 for the arms and the similar balls 10 for the legs have holes 12 in their center large enough to permit the rocking of the said members in their sockets within operating limits and yet not bend or strain 85 the said links 5 across the edges of said holes. The sockets in the arms and legs for said balls are of a sufficient width to engage over or upon the balls and to permit the attachment of the said links 5 by the washers 90 7 and the disks 8, which latter usually are of the same material as the doll itself. The fact that the attachment of links 5 is made in the manner shown in or upon the outer 95 wall of the arms and legs makes it imperative that the sockets should be in the arms and not in the body of the doll as otherwise such attachment would be impossible. Normally the connection between the arms is directly or straight across from one to the 100 other by means of spring 4, and this relation of the spring does not change however 105 the arms may be turned or adjusted.

Connected with the links 5 of the legs are the extension links 14 and 15 on each side, and the latter have a swivel connection with a link 16 on a single central spring 17 5 united at its upper end by link connection 20 with the head *h*. The said links 15 are preferably made of stiff sheet metal bent to right angles in their outer portions for the insertion of the swivel links 14 and provided with 10 holes in their inner ends and overlapped and connected by link 16 swiveled in said holes and attached to spring 17. The said several links 5, 14 and 15 are located and arranged to provide a central inward and upward 15 pull or tension on the balls and sockets of the legs 1, and said connections are accordingly highest at the center where they engage with spring 17 adapted to exert an upward pull and incline thence outward to the 20 legs. The said legs are thus provided with independent rotation in their sockets with the swivel in the part 15. The spring 17 unites the said legs or their flexible connections with the head *h*, which brings the said 25 parts into working relations under the same tension and with but a single central spring through which the tension on the said parts is effected and equalized. In this connection it will be observed that the said legs are located practically at the side of body *b* but 30 have their bearings or sockets at a slight inward inclination at the bottom so that the legs can be swung bodily around on their sockets in either direction, as may also the 35 arms *a*, and either may be so rotated regardless of the position of the other.

What I claim is:

1. A doll having a hollow body and hollow arms and legs and provided with ball 40 and socket joints for the said arms and legs, and flexible connection between the arms and between the legs having beads swiveled on the inside of the walls thereof.
2. A doll body having hollow arms and 45 legs socketed thereon, flexible connection between said members respectively provided with beads at their ends and metallic washers secured over said beads on the walls of said parts.
3. A doll having hollow members socketed on the body thereof, and flexible spring 50 connections through said body having swivel engagement on the inside of the outer walls of said members, said engagement comprising a metallic washer and a disk over said

washer permanently adhered to said wall about the edge of the washer.

4. A doll having hollow members socketed on the side of the body thereof, a spring tension connection through said sockets having beads at its ends, metal washers over 60 said beads on the walls of said members and means over said washers confining the same in working position on said walls.

5. A doll having hollow arms socketed 65 thereon, a single transverse spring and links at the ends thereof provided with balls engaged in the outer wall of said arms and means confining said balls in working position against the wall of said arms. 70

6. A doll having hollow legs socketed thereon, a transversely disposed connection swiveled at its ends in the outer wall of said legs and an equalizing spring engaged with the middle of said connection. 75

7. A doll provided with a hollow body and hollow legs socketed on the sides thereof, transversely disposed swivel connections between said legs, and a spring attached to the middle of said connections and to the head 80 of the doll and in tension relations with the said head and the said connections respectively.

8. A doll having legs socketed at the sides thereof, a flexible substantially transverse 85 connection between said legs swiveled in the legs at its ends, a head socketed on the body of the doll and a spring interposed between said head and the said transverse connection. 90

9. A doll body having legs socketed thereon and cross connections between said legs holding the same on said sockets, said connections provided with swivels in the legs and a single equalizing spring engaged with 95 said connections and anchored at the top of said body.

10. A doll body having a head and legs socketed thereon, in combination with a tension mechanism connecting said several 100 parts comprising a single spring linked to said head and a transverse disposed connection between said legs having said spring attached to the middle thereof.

In testimony whereof I affix my signature 105 in presence of two witnesses.

FREDERICK WILLIAM PARSONS.
